United States Patent Office.

JESSE F. TAPLEY, OF SPRINGFIELD, MASSACHUSETTS.

Letters Patent No. 106,232, dated August 9, 1870.

IMPROVEMENT IN PHOTOGRAPH ALBUMS.

The Schedule referred to in these Letters Patent and making part of the same.

Be it known that I, JESSE F. TAPLEY, of Springfield, in the county of Hampden and State of Massachusetts, have invented a new and improved Photograph Album; and I do hereby declare that the following is a full and exact description of the same, reference being had to the accompanying drawings and to the letters of reference marked thereon.

To enable others skilled in the art to make and use my invention, I will proceed to describe its construction and use.

Figure 1 in the accompanying drawings represents the album, complete.

Figure 2, a sectional view of the album, showing the manner of putting the leaves together and fastening the cover on.

Figure 3, a sectional view of the leaf, showing the position of the card in the leaf, and the method of inserting it.

Figure 4 is a view of the leaf, showing, by the cross-hatched part, where it is pasted together, and the guard pasted on, the black marks A A showing, also, the slits cut for inserting the cards.

In making the leaf, I take two pieces of paper, one of which is cut about an inch wider than the other. Through one of these the slits (see A A, fig. 1,) are cut for inserting the pictures. I then paste the two pieces together near the edges of the smaller piece, and crosswise through the center of the leaf, leaving sufficient space unpasted for the pictures, as shown in fig. 4, being careful to have three edges of the two pieces come evenly together, which would leave to each leaf a single thickness of the paper forming the leaf projecting beyond the other, (see B B,) which I use to

fasten the leaves together; and as a hinge to turn them upon.

Having formed the leaves in this way, I cut strips of pasteboard or paper (see C C) of sufficient thickness to make the back of the album as thick as the body of the book or leaves will be when filled with pictures, and, after pasting one piece on the single thickness of each of the leaves, I take as many of the leaves as I wish to put into a book, and paste the part having the strips of pasteboard on, and form the book by laying the leaves evenly together, and placing a weight upon the pasted part until it is set, when the body of the book is made.

The cover being nailed to the book, (fig. 2, D D,) it is necessary to provide for its opening freely. This I do by making the boards of each cover in two parts, a narrow piece through which the nails pass, and a wide one for the plain cover or part that opens, and the leather or cloth, which forms a hinge, as shown at E E, figs. 1 and 2, on which the cover can be swung back and forth with ease.

What I claim, and desire to secure by Letters Patent, is—

The album-leaf with openings for pictures, composed of two pieces of paper, wherein one is wider than the other, for the purpose of forming a flexible hinge, in combination with the pieces of board to fill the back, and the cover having flexible joints, as described.

J. F. TAPLEY.
